UNITED STATES PATENT OFFICE.

EDWIN H. NELSON, OF DETROIT, MICHIGAN.

DESIGN FOR A BOTTLE.

SPECIFICATION forming part of Design No. 25,403, dated April 21, 1896.

Application filed March 10, 1896. Serial No. 582,654. Term of patent 7 years.

To all whom it may concern:

Be it known that I, EDWIN H. NELSON, a citizen of the United States, residing at Detroit, in the county of Wayne and State of Michigan, have invented and produced a new and useful Design for Bottles, of which the following is a specification, reference being had therein to the accompanying drawings, showing a part thereof.

Figure 1 is an elevation of a bottle of my design. Fig. 2 is a plan of the same with the rim broken off.

A is the body; B, the cylindrical neck; C, the rim around the mouth, and D the intervening tapering portion between the body and neck. The body portion is substantially square-shaped in cross-section, and the leading feature of the design consists in making said body portion with four quarter-round

corners E and continuing and producing said corners upwardly through the intervening tapering portion D, and thence into the neck B, which is formed by the confluent upward extensions thereof. The body portion between the quarter-rounds is formed with flat sides, which continue upwardly into the tapering portion D, in which they taper to a point G at the base of the neck.

What I claim as my invention is—

The design for a bottle substantially as herein described and shown.

In testimony whereof I affix my signature in presence of two witnesses.

EDWIN H. NELSON.
